UNITED STATES PATENT OFFICE.

CHARLES E. BARRETT AND JOHN H. HORNE, OF LAWRENCE, MASSACHUSETTS, ASSIGNORS TO THE J. H. HORNE & SONS COMPANY, OF SAME PLACE.

PAPER-MAKING MACHINE.

SPECIFICATION forming part of Letters Patent No. 634,228, dated October 3, 1899.

Application filed April 19, 1899. Serial No. 713,567. (No model.)

To all whom it may concern:

Be it known that we, CHARLES E. BARRETT and JOHN H. HORNE, of Lawrence, county of Essex, and State of Massachusetts, have invented an Improvement in Paper-Making Machines, of which the following description, in connection with the accompanying drawings, is a specification, like letters on the drawings representing like parts.

10 The present invention relates to a Fourdrinier paper-machine and is embodied in that part of the machine known as the "shake-frame," at which part the pulp is first supplied to the wire support and "laid" by a lateral vibration thereof.

15 In certain kinds of pulp, notably the wood-pulp which is now largely used in making paper, the water drains away very rapidly, so that the pulp may become nearly dry before it leaves the shake-frame, and thus not be properly laid when it reaches the rollers. This tendency may be obviated to a considerable extent by downwardly inclining the shake-frame toward the rollers, so that the 20 water tends to travel along with the pulp and will not, therefore, drain out through the wire so rapidly. It is further desirable that the amount of inclination or slope should be variable, so as to adapt the machine for pulp of 25 different kinds or grades.

30 It is the object of this invention to accomplish these purposes, and in accordance therewith the shake-frame is mounted on a movable support or frame, the end of which where 35 the pulp is received being arranged to be raised or lowered, so that the said shake-frame can be inclined at any angle to the permanent rails, or, if desired, retained level. The ends of the shake-rails where they adjoin the stationary support are so arranged that they are 40 not raised or lowered in the adjustment of this part of the machine, the adjusting movement having this point as an axis. As herein shown, the stationary rails and the shake- 45 rails are both supported adjacent to each other upon an upright at the end of the adjustable staging, the stationary rails being so arranged that said upright is capable of a slight pivotal movement with relation to said rails, so 50 that as the staging is raised the stationary

rails will not be strained and will always remain at the same level with the pivoted ends of the shake-rails.

Figure 1 is a side elevation of a portion of a Fourdrinier paper-machine, showing the 55 shake-rails and sufficient of the stationary rails to illustrate the relation between said parts; and Fig. 2 is an end elevation of the same, the floor or main supporting portion of the room in which the machine is placed being shown in section in both figures.

That portion of the machine which comprises the shake-rails A, the deckle-strap B, the table-rolls C, and the wire D, all of which parts are of usual construction, is mounted, 65 in accordance with the present invention, upon a movable frame or support, herein shown as comprising longitudinal beams a and transverse beams b, the former constituting the main support for the machine elements above-named. The said frame is shown as provided at one end with vertical members or supports a², to which the shake-rails A are pivoted at A², the said shake-rails being supported at the opposite end upon rolling supports A³, substantially as shown and described in Patent No. 595,753, granted December 22, 1897, to Charles E. Barrett. In this instance, however, the said rolling supports instead of resting on the floor rest upon the beams a of 70 the movable frame or support for this part of the machine. Since the shake-frame carries the breast-roll, the table-rolls, &c., it is obvious that the inclination or slope of this part of the machine, including the wire, will be 75 varied by raising or lowering the end of the frame or support a b. Since the wire extends directly from this part of the machine to the part where the stationary rails E are supported, it is essential that the end of the 80 shake-rails should be adjacent to the ends of the permanent rails, and, as herein shown, the permanent rails rest upon the uprights a², being loosely connected therewith and beveled at E², so that the said post can be rocked 85 with relation to said fixed rails without straining the same. This part therefore constitutes the axis upon which the whole frame is moved when the opposite end thereof is lifted or lowered, and to accommodate such move- 90 95 100

ment the frame is shown as provided with wheels or other antifriction devices a^3 , resting upon a pillar or support a^4 , which is preferably below the floor of the room in which the machine is placed, in order that the upper portion of the frame a may be substantially on a level with the said floor. When, therefore, the farther end of the frame is lifted or lowered, the wheel a^3 will travel along the surface of the post a^4 , the shake-rails and the permanent rails remaining in the same position with relation to each other.

The end of the frame a may be raised or lowered by any suitable means, it being desirable, however, to arrange a compensating gear, since the frame is exceedingly heavy, while the distance through which it is to be moved is relatively small. As herein shown, the said frame is supported upon cams c , the beams a being provided with wheels a^5 or other suitable antifriction devices resting on the said cams, one of which is below each side beam. These cams are shown as secured upon a shaft c^2 , provided with bearings c^3 , supported upon pillars c^4 , corresponding to the pillars a^4 and preferably below the surface of the floor F . To operate the cams, the shaft c^2 is shown as provided with a gear-wheel c^5 , coöperating with a worm d , which is shown as mounted on a vertical shaft d^2 , provided with an actuating-wheel d^3 . The said shaft is mounted in a suitable bearing d^4 upon the floor F , so that the wheel d^3 will be in a convenient position to be actuated by the attendant. To raise the end of the frame a , therefore, in order to produce the desired inclination or slant of the wire part, it is only necessary to turn the wheel d^3 , and thus cause the rotation of the shaft c^2 , so that the cams turn, thereby gradually lifting the entire frame at this end until it has reached the desired position. The nature of the gearing is such that no locking devices are necessary, it being obvious that the frame will be supported in any desired position until changed by turning the wheel d^3 .

We claim—

1. A movable staging or support for the shake-frame of a paper-machine; and means for changing the vertical position of the breast-roll end of said support without changing the vertical position of the opposite end thereof, to thereby vary the inclination of the wire upon the shake-frame, as set forth.
- 50

2. A movable staging or support for the shake-frame of a paper-machine, said staging being independent of the support for the remainder of the machine, one portion of said staging also constituting a support for the stationary rails; and means for vertically adjusting the position of the breast-roll end of said staging without varying the vertical position of that part which constitutes the support for the stationary rails, as set forth.

3. A movable staging or support for the shake-frame of a paper-machine, said staging being provided at one end with vertical members to which the shake-rails are pivoted, (said vertical members also constituting supports for the stationary rails) and at the other end with a vertical support for the breast-roll; rolling-supports for said staging below the vertical members at the stationary rail end of the staging; and vertically-adjustable members to support said staging near the breast-roll end thereof, as set forth.

4. A movable staging or support for the shake-frame of a paper-machine; one or more cams upon which said staging rests at the breast-roll end; and means for rotating the said cams to vary the vertical position of said breast-roll end of the staging, the other end being arranged to maintain the same vertical position, as set forth.

5. A movable staging or support for the shake-frame of a paper-machine, one or more cams upon which the breast-roll end of the said staging rests, a gear-wheel connected with said cams and adapted to rotate the same, and a worm coöperating with said gear to vary the vertical position of the breast-roll end only of said staging, substantially as and for the purpose described.

6. A movable staging or support for the shake-frame of a paper-machine, the breast-roll end of which said staging is adapted to be raised or lowered to vary the angle of the wire support along the shake-frame to the said wire support beyond the said shake-frame, substantially as described.

In testimony whereof we have signed our names to this specification in the presence of two subscribing witnesses.

CHARLES E. BARRETT.
JOHN H. HORNE.
